WIRE SPRING CONSTRUCTION FOR UPHOLSTERED FURNITURE

William H. Neely, Cleveland, Ohio, assignor, by direct and mesne assignments, to John C. Lincoln, Scottsdale, Ariz.

Application December 27, 1939, Serial No. 311,144

7 Claims. (Cl. 155—179)

This invention relates in general to spring seat structures for automobile and upholstered furniture seats embodying elongated wire springs of sinuous or similar shape such as described in my co-pending application Ser. No. 256,277, and more particularly to a unitary spring seat structure in which an open frame is bridged by elongated wire springs mounted parallel to each other in elevated position crosswise of said frame. A seat structure of this type, which has the seating portions of the individual springs yieldingly interconnected to a unitary seating surface by short helical springs encircled at its side and front edges by a border or edge wire reenforcing these edges, necessitates heavier, or reenforced, outer springs, due to the fact that these springs mount the edge wire but are only supported at their inner sides by adjacent springs. Heavier or reenforced outer springs of course interfere with proper yielding action of the outer areas of the seating surface and change the resiliency of the entire seating structure.

It is the primary object of the present invention to overcome the above stated deficiencies in present day spring seat structures of the type referred to by the provision of a spring seat structure in which all wire springs are substantially of equal yielding and supporting action and in which the edge wire which encircles the seating surface of the structure is pretensioned and attached to the sides of the outer springs and the frame to effect proper support of these outer springs by said edge wire.

Another object of the invention is the provision of a uniformly yielding, supporting spring seat structure of the type described, assembled from elongated wire springs of substantially equal resiliency, and a torsionally tensioned border or edge wire, which wire is coupled with the outer sides of the outer springs and the frame, to effect proper support of said outer springs.

A further object of the invention is the provision of a uniformly yielding, supporting spring seat structure of the type described, assembled from elongated wire springs of substantial equal resiliency, and a torsionally tensioned U-shaped border or edge wire, which wire is coupled with the front ends of all said springs, the outer sides of the outer springs and the frame in such a manner as to prohibit lateral movements of the seat structure and effect equal support of all springs including the outer springs.

With these and incidental objects in view, the invention consists in certain other novel features of construction and combination of parts,

the essential elements of which are set forth in the appended claims, and a preferred form of embodiment of the invention is hereinafter shown with reference to the drawings accompanying and forming a part of this specification.

In the drawings:

Fig. 1 is a top elevation of a seat structure embodying the invention, parts being broken away to show the corrugated wire springs, their hook-up with a torsionally tensioned U-shaped border wire, and the hook-up of said tensioned border wire with the frame of the seat structure.

Fig. 2 is a side view of the seat structure shown in Fig. 1.

Fig. 3 is a plan view of the U-shaped border wire.

Fig. 4 is a plan view of a stiffening wire extension member used in the structure shown in Fig. 1 to give the seating surface of the structure the desired outline; and

Fig. 5 is an enlarged fragmentary, perspective view of the rear rail of the frame showing springs secured thereto, and the border wire coupled to said rail.

Referring now more particularly to the exemplified form of the seat structure shown in Figs. 1 and 2 of the drawings, reference numeral 2 denotes a tubular, substantially rectangularly shaped open seat frame structure. This structure is made of tubular piping and has its side rails 3, 3' bent upwardly, so that the rear rail 4 is elevated with respect to front rail 5 and provides ample space for yielding action of elongated, corrugated wire springs 6 which bridge the frame crosswise and are secured to the rear and front rails 4 and 5.

Springs 6, which are made of steel wire bent to sinuous shape to permit of longitudinal yielding stretching under load, are built similar to the springs of my co-pending application above referred to. Thus, each spring 6 is at the front end of its seating portion formed with an integral, rearwardly and downwardly extended supporting arm 7 which is looped at its lower end to provide a coil 8. The end of this coil 8 extends forward and is looped to form a second coil 9, which has its free end portion forwardly and laterally extended as at 10 and then doubled back as at 11 to form a hook-shaped supporting and attaching member 12 adapted to rigidly secure the front end of spring 6 to front rail 5 as more clearly brought out in co-pending application Ser. No. 215,526 of which applicant is co-inventor. The rear end of each spring is bent upwardly and formed with a coil 14 and a hook

15 including a straight extension 15' similar to the supporting and attachment means at the front of the spring, so as to permit of rigidly securing the rear end of the spring to rear rail 4. The thus mounted springs 6 are symmetrically distributed over the frame structure and are coupled with each other by short helical tension springs 16 to form a continuous seating surface adapted to support padding and covering, all as customary in the art.

Preferably, as shown, the outer springs 6' of the thus formed spring assembly each support and are coupled with elongated, lateral extension members 17 of the type described in the above referred to application Ser. No. 215,526. Each of these extension members 17, see Fig. 4, is formed from wire bent to substantial U-shape and provided in its web portion 18 with a U-shaped loop 19 adapted to engage and interlock with one of the loops 20 of outer springs 6' to prevent pivotal downward movement of the extension member with respect to springs 6'. Loop 19 embodies in its parallel sides 21 struck-up portions 22 which form recessed seats and permit of proper alignment of the extension member with the seating surface of springs 6'. The front end arm 23 of member 17 is substantially longer than its rear end arm 24 for proper attachment of said front end arm to end spring 6' and the adjoining springs 6, and, preferably, arms 23 and 24 are provided with properly spaced recesses 25 to precisely locate the position of member 17 and prevent lateral shifting of said member when clips 26 fasten arms 23 and 24 to springs 6 and 6'.

The thus constructed seating surface of the spring assembly has its front and side edges encircled by a substantially U-shaped edge wire 27, embodying a web portion 28, side arms 29 and relatively short torsion arms 30. These torsion arms extend inwardly from the rear ends of side arms 29 in substantially parallel relation with respect to web portion 28 and have their free ends formed with crank arms 31 ending in hook members 32 to permit of said arms being hooked to the protruding straight extensions 15' of the rear supporting and attachment means for springs 6 which adjoin outer springs 6'.

In addition, crank arms 31 are angularly related to side arms 29 of edge wire 27 in such a manner as to effect torsional tensioning of torsion arms 30 when hook members 32 engage extensions 15' and side arms 29 and web 28 are forced downwardly substantially into the plane of the seating surface for connection with web 18 of member 17 and with the front ends 33 of springs 6 by means of clips 34. A torsional tension in torsion arms 30 provides additional support of springs 6' and extension members 17, and hook members 32, when engaged with extensions 15', prohibit lateral movements of the seating surface.

Preferably, outer springs 6' have a slightly shorter seating surface than springs 6, an arrangement which effects a somewhat different inclination of the V-shaped front supporting means of said springs and therewith slightly stiffens springs 6' without materially affecting the yieldability of their seating portions. Torsion arms 30 are dimensioned to extend through coils 14 of springs 6' and to engage with their hook members 32 extensions 15' on the springs 6 which are adjacent to springs 6'.

During assembly procedure, after springs 6 and 6' have been attached to the rear and front

rails 4 and 5 of frame 2, extension members 17 are sleeved upon the respective loops 20 of springs 6' and secured thereto by clips 26. Then torsion arms 30 of U-shaped border wire 27 are threaded through coils 14 of springs 6' in such a fashion that extensions 15' of said springs form supports for said torsion arms, and finally the hook members 32 are hooked upon extensions 15' of springs 6. In this position, the web portion 28 of border wire 27 is positioned a substantial distance above the seating surfaces of springs 6 and 6' and must forcibly be shifted downwardly to permit of attachment to the front ends 33 of springs 6 and attachment of side arms 29 to extension members 17. Such forcible movement pre-tensions the edge wire by the torsional effect on torsion arms 30 and thus provides the desired additional support for springs 6 and extension members 17.

The spring assembly is of course padded and covered by a covering 35 and provides a comfortable, readily yielding seat structure with properly supported side areas and edges adapted to stand up under adverse conditions.

Having thus described my invention, what I claim is:

1. In a seat structure a frame having front and rear rails, a plurality of elongated wire springs bridging said frame crosswise thereof and secured to said front and rear rails, means inter-connecting said wire springs to a seating surface, and a torsionally pre-tensioned edge wire secured to the front ends of said springs, the outer sides of the outer ones of said springs and to the rear rail of said frame.

2. In a seat structure a frame having front and rear rails, a plurality of elongated wire springs bridging said frame crosswise thereof and secured to its front and rear rails, means inter-connecting said wire springs to a seating surface, and a pre-tensioned U-shaped edge wire including torsional supporting and attaching arms, said edge wire being connected to the front ends of said springs and the outer sides of the outer ones of said springs and said torsional supporting arms being non-rotatably connected to the rear rail of said frame.

3. In a seat structure a frame having front and rear rails, a plurality of substantially equally shaped and tensioned corrugated wire springs arranged side by side crosswise of said frame and secured to the front and rear rails thereof, means interconnecting said springs to a seating surface, and a pre-tensioned U-shaped edge wire including inwardly extended torsional arms of substantial length having at its ends means angularly related to said arms for connecting said arms to said frame, said edge wire being connected to said springs, its side arms being connected to the outer sides of the outer springs and its torsional supporting arms, being arranged parallel to said rear rail, torsionally tensioned and by their angularly related means connected to said rear rail.

4. In a seat structure a frame having front and rear rails, a plurality of elongated, corrugated wire springs bridging said frame crosswise thereof and secured to said front and rear rails, means coupled with the outer ones of said springs for stiffening and widening their seating surfaces, and a torsionally pre-tensioned edge wire of U-shaped form coupled with all said springs, said stiffening and widening means and the rear rail of said frame.

5. In a seat structure a frame, a plurality of

elongated, corrugated wire springs bridging said frame crosswise thereof and secured to opposite rails of said frame, yielding means interconnecting said wire springs to a seating surface, corrugated means coupled with the outer ones of said springs for stiffening and widening their seating surface, and a U-shaped edge wire including torsional supporting arms, said edge wire being secured to said springs and said stiffening and widening means, and the torsional arms of said edge wire being torsionally tensioned and secured to said frame.

6. In a seat structure a frame, a plurality of elongated, corrugated wire springs bridging said frame crosswise thereof and secured to opposite rails of said frame, yielding means interconnecting said wire springs to a seating surface, corrugated means rigidly and non-rotatably coupled with the outer ones of said springs for stiffening and widening the side areas of said seating surface, and a U-shaped, pre-tensioned edge wire

including torsional supporting arms secured under torsional tension to the frame, said edge wire being secured to the front of said springs and to the sides of said stiffening and widening means.

7. In a seat structure a frame, a plurality of elongated, corrugated wire springs of equal length bridging said frame crosswise thereof and secured to opposite rails of said frame, a corrugated, shorter wire spring at each side of the surface formed by said first springs to a continuous seating surface, corrugated means rigidly and non-rotatably coupled with the shorter ones of said wire springs for stiffening and widening the side areas of the said seating surface, and a U-shaped, pre-tensioned edge wire including torsional supporting arms secured under torsional tension to the frame, said edge wire being secured to the front of said springs and to the sides of said stiffening and widening means.

WILLIAM H. NEELY.
